UNITED STATES PATENT OFFICE.

EMIL KNOEVENAGEL, OF HEIDELBERG, GERMANY, ASSIGNOR TO THE FIRM OF ATHION, GESELLSCHAFT MIT BESCHRÄNKTER HAFTUNG, OF MANNHEIM-WALDHOF, GERMANY.

PROCESS OF OBTAINING GASES FOR HEATING PURPOSES.

1,178,858.

Specification of Letters Patent.

Patented Apr. 11, 1916.

No Drawing.

Application filed September 15, 1913. Serial No. 789,922.

To all whom it may concern:

Be it known that I, EMIL KNOEVENAGEL, a subject of the German Emperor, and resident of Heidelberg, Germany, have invented 5 certain new and useful Improvements in Processes of Obtaining Gases for Heating Purposes, of which the following is a specification.

It is known that carbon-containing fuels 10 may be gasified at high temperatures by means of carbonic acid, gases consisting mainly of carbon monoxid being thereby formed. No firing with carbon monoxid has yet been based on this process, because there 15 were not suitable sources of cheap, high percentage carbonic acid.

It has not hitherto been known to utilize 20 the carbonic acid of the smoke gases for firing with carbon monoxid and to recuperate the carbonic acid by a cyclic operation.

The present process is based on the absorption 25 of the carbonic acid from smoke in any known manner either chemical or mechanical, for instance by means of carbonates or of water, the carbonic acid extracted containing a high percentage of CO_2 , and then being used to gasify at high temperatures fuels containing a high percentage of carbon. The gases thus obtained consisting 30 mostly of carbon monoxid are then used for heating purposes and in firing installations, working under pressure if needs be, thereby again forming smoke gases containing carbonic acid, about 50 per cent. of which are 35 again used in the cyclic operation.

The process presents the advantage that considerable amounts of pure carbonic acid (the remaining 50 per cent.) can be extracted for liquefaction for known purposes, 40 such for instance as the production of cold, the operation of motors or the like.

The process is especially economical as it 45 is possible in recovering the carbonic acid from the smoke gases, to wash out at the same time by suitable washing processes the nitrogen compounds present in the smoke gases for instance in the form of combinations of nitrogen and oxygen and of ammonia.

50 It is thus possible to profitably obtain the compounds of nitrogen and oxygen produced in the combustion of carbon monoxid, the formation of which compounds is promoted by the cooling effect which the heat-

ed surfaces exercise on the gases that are being burnt in the firing installations.

The carbonic acid obtained from the smoke gases can in this process be used in various ways for the gasification of the fuels containing carbon, for instance the carbonic acid can be led under the shaft of a producer furnace and utilized for increasing the content of carbon monoxid in the producer gases. In this manner it is possible to simultaneously obtain in consequence of the endothermic character of the process, a reduced temperature in the producer furnaces and an extension of the firing zone, thereby increasing the duration of the producers. The gas thus produced corresponds to a mixed gas in which instead of steam, carbonic acid with air have been simultaneously introduced into the producer, forming an enriched producer gas.

Almost pure monoxid of carbon is obtained if the carbonic acid is, as in the water gas process, so employed that a hot blowing and a subsequent cold blowing take place periodically in the producer furnace, the resulting gases being collected separately, whereby in the first phase (as in the water gas process) producer gas will be formed, while in the second phase almost pure carbon monoxid (in lieu of water gas) is produced. This process can also be carried out even under pressure in apparatus heated in any suitable manner for the permanent production of almost pure carbon monoxid. The combustion of the carbon monoxid gases thus produced is preferably effected in accordance with gas firing under pressure, for the purpose of securing a better mixing of the gases and a more rational heating together with an increased yield of compounds of nitrogen and oxygen, without, if needed, allowing the gases to partly, or fully, expand during their combustion.

From the products of combustion of these carbon monoxid gases, the compounds of nitrogen and oxygen are obtained in any suitable manner for instance by cooling or in washing apparatus in the usual manner, for instance by washing with water, or both methods.

After the compounds of oxygen and nitrogen have been separated out from the smoke gases, the extraction of the carbonic acid is effected in the usual manner, preferably in

2
special washing apparatus, for instance with a solution of potassium carbonate. From the lye saturated with carbonic acid, the latter is recuperated in the known manner for instance by heating, and thereupon used afresh in the cyclic operation for gasifying fuel, or, if desired, it is liquefied after being suitably purified and dried.

A special advantage of the process in accordance with this invention lies in the fact that the smoke gases do not reach the atmosphere until after they have been purified.

What I claim is—

1. The cyclic process of obtaining heating gases which consists in gasifying carbon-containing fuels by means of carbon dioxide, thereby forming carbon monoxide, burning the carbon monoxide with air, recovering the compounds of nitrogen and oxygen from the products of combustion, then recovering the carbon dioxide from such products of combustion, and again passing a portion of the

separated carbon dioxide over the heated carbon-containing fuel.

2. The cyclic process of obtaining heating 25 gases which consists in gasifying carbon-containing fuels by means of carbon dioxide, thereby forming carbon monoxide, burning the carbon monoxide with air, recovering the compounds of nitrogen and oxygen from 30 the products of combustion, then recovering the carbon dioxide from such products of combustion as a carbonate, recuperating the carbon dioxide from the carbonate and thereupon passing it over heated carbon-containing 35 fuel.

In testimony whereof I have signed my name to this specification in the presence of two subscribing witnesses.

EMIL KNOEVENAGEL.
